DESIGN FOR A LADY'S SWEATER

Hans Boepple, New York, N. Y.

Application April 19, 1935, Serial No. 56,463

Term of patent 3½ years

To all whom it may concern:

Be it known that I, Hans Boepple, a citizen of the United States of America, residing in Manhattan, county of New York, and State of New York, have invented a new, original, and ornamental Design for a Lady's Sweater, of which the following is a specification, reference being had to the accompanying drawing, forming part thereof, wherein,

I claim:

The ornamental design for a lady's sweater, substantially as shown.

HANS BOEPPLE.
